ORNAMENT FOR WHEEL COVERS

Clarence D. Zierhut, Granada Hills, Calif., assignor to Shore-Calnevar, Inc., Paramount, Calif., a corporation of California

Filed Feb. 13, 1961, Ser. No. 63,903

Term of patent 14 years

(Cl. D14—30)

FIG. 1 is a front elevational view of an ornament for wheel covers, showing my new design;

FIG. 2 is a top plan view thereof;

FIG. 3 is a side elevational view thereof; and

FIG. 4 is a cross-section taken along the line 4—4 of FIG. 1.

I claim:

The ornamental design for an ornament for wheel covers, substantially as shown.
